UNITED STATES PATENT OFFICE

FRANK C. SUTLIFFE, OF SAN FRANCISCO, CALIFORNIA

ILLUMINATED SIGN

Application filed June 12, 1929. Serial No. 370,284.

The invention relates particularly to illuminated signs of the rotary type.

The primary object of the invention is the provision of a rotary sign, the illuminating element of which is rotated when the sign is in operation, means being provided to connect said sign and said rotating illuminating elements to a source of electricity at all times.

Another object of the invention is the provision of an illuminated sign in which a plurality of light elements of different colors are displayed and rotated, said light elements being connected to a source of electricity in series, so as to allow the continuous flow of electricity thru the light elements during the rotation of the sign.

A further object of the invention is the provision of an illuminated sign, in which a plurality of spiral light elements of different colors are disposed in a winding form somewhat similar to the windings of triple threads; said elements are connected in series with each other, means being provided to connect the series of elements to a source of electricity so as to assure a continuous contact and connection when the elements are rotated as a unit around the axis of the spirals.

Particularly it is the object of my invention to provide an illuminated barber pole or the like sign, in which a plurality of spiral neon tubes are arranged for unitary rotation around a central axis common to all of said spirals; said tubes being filled with different gases producing different color effects when connected to a source of electric current; means being provided for the rotation of the tubes as a unit; and for establishing the series connection of said tubes with the source of electric current at all times.

Other objects and advantages are to provide an illuminated sign of the rotary type, that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in

other forms; and it is also to be understood that in and by the claims following the description, it is desired to cover the invention in whatsoever form it may be embodied.

The invention is clearly illustrated in the accompanying drawing in which

Fig. 1 is a longitudinal sectional view of the illuminated rotary sign constructed in accordance with my invention;

Fig. 2 is a side view of an end of the rotary element of the sign; and

Fig. 3 shows end views of the opposite ends of the rotary element of my sign, and the wiring diagram of the connection of the rotary element to a source of electricity.

In carrying out my invention I make use of three spiral neon tubes 5, 6 and 7, wound spacedly around a central shaft 8 as an axis. Each tube is filled with suitable gas for producing illumination of a certain color when electric current is passed therethru. Tube 5 is filled with a gas producing red color; tube 6 provides white illumination; and tube 7 provides blue color. The above mentioned color combination is preferred in connection with barber poles, however, any other suitable color combination may be effected, if so desired. The gases in the usual neon tubes, for the different colors, have different resistance to the flow of electric current, therefore it is preferable to connect the neon tubes in series with a source of electricity.

The connection of the tubes 5, 6 and 7 to each other and to a source of electricity is accomplished on circular disks 9 and 11, upon which the ends of the tubes 5, 6 and 7 are supported. The disks 9 and 11 in turn, are mounted on the shaft 8 so as to rotate therewith. On the disk 9 are electrodes 12, 13 and 14 connected respectively to the ends of the tubes 5, 6 and 7. On the other disk 11 are mounted electrodes 16, 17, and 18 connected respectively to the other ends of the tubes 5, 6 and 7. In order to connect the tubes 5, 6 and 7 in series the electrodes 13 and 14 are connected to each other at the upper end of the tubes, and the electrodes 16 and 18 at the lower ends of the tubes, are also connected to each other, thus allowing a continuous flow of electric current from the electrode 12 thru

tube 5, then thru electrodes 16 and 18, and thru the tube 6, to electrodes 13 and 14, and thru the tube 7 to electrode 17. The flow of electric current thru the tubes causes the 5 illumination thereof in their respective colors.

Now by the rotation of the shaft 8, the entire illuminated structure is rotated, presenting, in the present illustration, the 10 appearance of an illuminated barber pole. In order to allow the transmission of electricity to the electrodes 12 and 17, while the sign is rotated, a ring contact 19 is connected to the electrode 12 and another ring contact 21 is 15 connected to the electrode 17; both ring contacts 19 and 21 are concentric with the shaft 8, and are insulated from the shunted contacts 13 and 14 and 16 and 18 respectively by insulating disks 9 and 11.

20 In order to support the entire revolving unit heretofore set forth, I provide opposed brackets 23 and 24, adapted to be attached to a wall or to any other supporting surface. The brackets 23 and 24 are spaced from each 25 other and the inner edges thereof have grooves 26 therein into which fits a transparent cylinder 27, preferably made of glass.

Electric conduits 28 and 29 extend respectively into the brackets 23 and 24. Each of 30 these conduits 28 and 29 is connected to a brush contact 31, one above the disk 9 and the other below the other disk 11. The brushes 31 are in contact with the respective contact rings 22 at all times.

35 The rotation of the shaft 8 is accomplished by an electric motor 32, on the shaft of which is mounted a worm 33, in mesh with a gear 34 on the shaft 8.

While the motor 32 rotates the shaft 8 and 40 the tubes 5, 6 and 7 as a unit therewith, the brushes 31 constantly connect the tubes to a source of electricity, which causes the glow of the gases in the tubes in the colors of red, white and blue respectively. The spiral 45 tubes thus rotating form the illuminated barber pole, in which the illuminating elements themselves are the different colored stripes, and are rotated around an axis common to all the spirals of the sign.

50 It will be recognized that a particularly facile illuminated sign is provided, which utilizes spiral illuminating tubes efficiently and with brilliant effect. The sign combines positiveness of operation, with a ruggedness 55 of construction and simplicity, especially adapting it for its use. The sign does not require any careful adjustment and setting up, and it may be readily assembled, connected, and operated by the average layman.

60 Different color combinations may be further achieved by using different colored tubes to blend with the color of the glowing gas in the tubes. Furthermore colored tubes of other types than neon tubes, may be similarly arranged and connected to produce the 65

brilliant sign effect heretofore set forth. In some instances straight tubes, or tubes curved otherwise than spirally may be employed and produce still further different illuminated signs. However, in all embodiments of my 70 invention, the tubes are connected to each other and to a source of electricity in such manner as to allow the rotation of the illuminating elements themselves without disturbing their electrical connections. 75

Having thus described this invention, what I claim and desire to secure by Letters Patent is:

1. An illuminated sign comprising a plurality of illuminating elements disposed in parallel windings and connected in series with each other; rotating means to carry said illuminating elements as a unit; means to rotatably support said rotating means; and means outside the space surrounded by the tubes to connect said elements to a source of electricity. 80

2. An illuminated sign comprising a plurality of parallel spiral, and tubular illuminating elements arranged to enclose a substantially cylindrical space; rotating means to support said elements in position; means outside of said space to connect said elements in series with each other and to a source of electricity; and a frame outside the tubes to 90 support said rotating means. 95

3. An illuminated sign comprising a plurality of spiral, illuminating tubes containing substances which glow when electric current is passed therethru and which offer different resistances to the flow of electricity therethru; said tubes being arranged to enclose a substantially cylindrical space; means outside of said space to connect said tubes in series with a source of electricity; means to support said tubes in fixed relation to each other and means to rotate said support and said tubes as a unit. 100 105

4. An illuminated sign comprising a plurality of spiral neon tubes of different colors and different resistances to the flow of electricity therethru; said tubes being arranged to enclose a substantially cylindrical space; means outside of said space to connect said tubes in series with a source of electricity; means to support said tubes in a substantially parallel position; a frame in which said supporting means is journaled; and means to rotate said supporting means with the spiral tubes thereon as a unit. 110 115

5. An illuminated sign comprising a plurality of parallel spiral and tubular illuminating elements filled with inert gas, means to support the opposite ends of the elements in fixedly spaced relation relatively to one another; an electrode on each end of each element; means on the supporting means outside of the space surrounded by the tubes to connect the electrodes so as to establish a series connection thru said element; a frame 120 125 130

in which the supporting means are rotatably supported; means to rotate said supports to carry said elements around its axis of rotation; and stationary contacts on the frame outside of said space being connected to a source of electricity and contacting with the respective connecting means to convey electricity to said series circuit.

5 6. An illuminated sign comprising a plurality of spiral, illuminating tubes containing substances which glow when electric current is passed therethru and which offer different resistances to the flow of electricity therethru; a frame; a rotary element having 10 spaced tube supports thereon, being rotatably mounted in the frame; an electrode at each end of each tube adapted to mount the respective ends of the tubes on the supports; means on each support to connect the ends 15 of certain tubes to each other so as to connect the tubes into a series circuit, conductor rings on the supports outside of the space enclosed by the tubes; stationary contact elements on the frame, each contacting with the adjacent 20 ring and being connected to a source of electricity; and means on the frame to rotate said rotary element and the tube supports together.

25 7. An illuminated sign comprising a frame, a shaft journaled in the frame, parallel discs secured to the frame, tubes of light transmitting material and containing rarefied gas arranged in parallel spirals being supported on the discs, connections in each disc to connect the tubes in series with each other, a 30 contacting ring on the outside of each disc connected to the adjacent terminal of the series of tubes, stationary contact members on the frame engaging the respective contact rings and being connected to a source of 35 electricity, and means to rotate said shaft and discs and tubes.

40 8. An illuminated sign comprising a frame, parallel supporting discs, means to rotatably 45 support the discs in the frame in aligned position, tubes of light transmitting material and containing rarefied gas arranged in parallel spirals and secured at the ends thereof to the respective discs, means on the disc 50 to connect the respective terminals of the tubes at each end so as to establish a series connection of all the tubes, contact members rotating with the discs and connected to the end terminals of the series of tubes, stationary 55 contact members on the frame engaging the respective rotating contact members and being connected to a source of electricity, and means in the frame to impart rotation to the said support means so as to rotate the 60 discs and the tubes therewith.

65 9. An illuminating sign comprising a frame, spaced discs in the frame, means rotatable in the frame to support the discs in spaced relation; a plurality of spiral tubes 70 of light transmitting material containing rarefied gas having the ends thereof secured to the discs, an electrode in each end of each tube, conducting means in the discs to connect the respective electrodes so as to establish a series connection through the tubes, 75 contact members rotating with the discs and being disposed outside of the space inclosed by the tubes, stationary contact members on the frame disposed outside of said space, engaging the respective rotating contact members and being connected to a source of electricity; and means on the frame to impart rotary movement to the said support means so as to rotate the discs and the tubes there- 80 with.

10 10. An illuminating sign comprising a frame, a shaft journaled in the frame, a pair of spaced discs fixed on the shaft, a plurality of spiral tubes of light transmitting material containing rarefied gas being disposed between the discs and spaced around the shaft, and having the ends thereof secured to the opposite discs, an electrode in each end of each tube, connecting conductors on the discs to connect the respective electrodes so as to establish a series connection of all of the tubes, contact rings on the outside of the discs being insulated from 85 said conductors but connected to the respective ends of the series of tubes, contact 90 brushes on the frame connected to a source of electricity and engaging the said contact rings, and means in the frame to impart rotary movement to the said shaft so as to rotate the discs and the tubes together.

95 In testimony whereof, I have hereunto set my hand at San Francisco, California, this this 6th day of June, 1929.
